(57) **CLAIM**

The ornamental design for an electric connector, as shown and described.

DESCRIPTION

FIG. 1 is a top, right, rear perspective view of an electric connector, showing my new design, shown open, in a first configuration for use;

FIG. 2 is a front elevation view thereof;

FIG. 3 is a rear elevation view thereof;

FIG. 4 is an enlarged left side elevation view thereof, the right side being a mirror image thereof;

FIG. 5 is a top plan view thereof;

FIG. 6 is a bottom plan view thereof;

FIG. 7 is an enlarged front elevation view of the detail identified in FIG. 2;

FIG. 8 is a bottom, right, front perspective view thereof;

FIG. 9 is an enlarged bottom, right, front perspective view of the detail identified in FIG. 8;

FIG. 10 is a left, front perspective view thereof;

FIG. 11 is an enlarged left, front perspective view of the detail identified in FIG. 10;

FIG. 12 is a top, left, rear perspective view thereof;

FIG. 13 is an enlarged top, right, rear perspective view of the detail identified in FIG. 12;

FIG. 14 is a top, right, rear perspective view thereof;

FIG. 15 is an enlarged top, right, rear perspective view of the detail identified in FIG. 14;

FIG. 16 is a bottom, right perspective view thereof;

FIG. 17 is an enlarged bottom, right perspective view of the detail identified in FIG. 16;

FIG. 18 is a bottom, left, rear perspective view thereof;

FIG. 19 is an enlarged bottom, left, rear perspective view of the detail identified in FIG. 18;

FIG. 20 is a top, right, front perspective view of the electric connector of FIG. 1, shown closed, in a second configuration for use;

FIG. 21 is a top, right, rear perspective view thereof; and,

(Continued)

FIG. 22 is a top, right, front perspective view of the electric connector of FIG. 20, shown at a reduced scale and in condition of use.

The broken lines form no part of the claimed design.
